LEADER PIN

Emil A. Baumbach, Chicago, Ill., assignor to
Advance Die Set Corporation, Chicago, Ill., a
corporation of Illinois

Application March 2, 1931. Serial No. 519,461

7 Claims. (Cl. 287—20)

My invention relates to leader pins, and more particularly to leader pins arranged to be secured in a die shoe to co-operate with a punch holder for the purpose of accurately aligning a punch 5 with a die.

This invention contemplates a removable leader pin wherein is provided a construction by which the pin may be firmly and securely positioned in an opening in the die shoe and which is 10 operable to allow the insertion or removal of the pin at any time.

A desirable feature is the provision of means entirely contained within the contour of the pin whereby the leader pin may be readily removed and replaced and will always be accurately positioned relative to the openings in the punch holder.

It is also an object to provide a securing mechanism enclosed within the contour of the pin 20 and in which the engaging means provides a cover completely enclosing the operating mechanism and preventing dust and dirt from entering therein.

Further objects will be apparent from the specification and drawing, in which drawing:

Figure 1 is a perspective view of a punch holder and die shoe incorporating an embodiment of my invention;

Fig. 2 is a side elevational view of one of the 30 leader pins in position in the die shoe, a portion of the leader pin and the die shoe being broken away for purposes of illustration;

Fig. 3 is a transverse sectional view through the leader pin and die shoe and taken on a line 35 corresponding to line 3—3 of Fig. 2, with the clamping ring turned slightly from the position of Fig. 2 and shown in section;

Fig. 4 is a detailed sectional view through the leader pin and taken on a line corresponding to 40 line 4—4 of Fig. 2; and

Fig. 5 is a detailed sectional fragmentary view of a portion of the retaining and clamping ring illustrating the means for preventing rotation of 45 the ring.

Referring to the drawing, the embodiment illustrated comprises a die shoe 1, in cooperative 50 relation with a suitable die and a punch holder 2 for supporting a punch which latter cooperates with a suitable die.

A pair of leader pins 3, removably secured in the die shoe, are extended through suitable guide holes 4 in the punch holder for the purpose of accurately aligning the punch and die.

55 The punch holder and die shoe may be of any

usual or suitable construction and are not described in detail.

The leader pins 3 are accurately machined to provide as nearly as possible a perfect sliding fit in suitable openings 5 in the die shoe; the fit 60

being such that the pins can be readily inserted and removed, but yet hold the pins firmly against any lateral movement in the openings. In order to secure a pin in the opening, a plurality of gripping pins 6 are slidably mounted in radially 65

disposed openings 7 in the lower end of the leader pin 3, and an adjusting screw 8, having a tapered conical end 9, is mounted in a threaded axial opening 10. The tapered conical end 9 is arranged 70

to engage the spherical inner ends of the gripping pins 6 so that when the screw 8 is operated the conical portion 9 will force the gripping pins outwardly. A resilient split clamping ring 11 is arranged in a slot 12 in a position to 75

retain the gripping pins 6 in assembled position when the leader pin is removed from the die holder. The ring 11 provides a suitable clamping means for engaging the die shoe and a groove 13 is provided in the die shoe to receive the ring 11 when it is pressed outwardly by the gripping 80

pins 6 as they are moved by the adjusting screw 8. The ring 11 is preferably of sheet metal and of curved cross-sectional contour, the outer contour conforming in shape to the groove 13 and the inner contour conforming substantially to the 85 curvature of the outer ends of the pins 6.

A hexagonal wrench 14 is arranged to be inserted in the hexagonal opening 15 for the purpose of turning the adjusting screw 8 for locking 90

and unlocking the leader pin in the die shoe. When the leader pin is inserted in the opening 5 in the die shoe the screw 8 will be in a lowered position, and the gripping pins will be pushed inwardly by the ring 11 and the ring will normally 95

be somewhat below the surface of the leader pin. In order to lock the pin in position in the die shoe, the screw 8 is operated to push the gripping pins 6 outwardly and the ring 11 will be forced into the groove 13, and the leader pin will thereby be held rigidly in position. The ends of the split ring 11 are turned inwardly at 16 thereby preventing the ring from rotating to a position where one of the gripping pins may enter slot 17 through radial openings 7.

In order to remove the leader pin, it is only necessary to turn the screw 8 in a direction to release the gripping pins 6 whereby the ring 11 will automatically be released from the groove 13. It will be seen that this construction is such 100

that the leader pins will be firmly held in the die 105

110

shoe without any chance of lateral or longitudinal movement and that they may be easily removed and replaced when desired.

It will be noted that the ring 11 substantially fills the slot 12 and completely covers the radial openings when the pin is removed from the die shoe thereby preventing dirt from entering therein; and providing a device which may be conveniently used or stored under the usual 10 machine shop conditions without injury.

While I have shown but one form of my invention, it will be understood that it may be embodied in other forms and I desire to be limited only by the prior art and the appended 15 claims.

I claim:

1. A leader pin for insertion in an opening in a support, a plurality of radially disposed laterally movable members in said pin, movable means 20 normally within the cylindrical surface of said pin for retaining said movable members normally within the contour of said pin and adjustable means for causing said retaining means to engage the walls of said support opening.
2. A leader pin for insertion in an opening in a support and having a lateral groove therein, a resilient member substantially filling said groove, radially disposed movable members in alignment with said groove and means for adjusting said movable members to cause the locking engagement of said resilient member with the walls of the opening in said support and to retain said leader pin therein.
3. A combined retainer and clamping ring for 35 a pin adjusting means of the character described comprising a resilient sheet metal split ring of concavo-convex cross-sectional contour, and inwardly extending portions on the ends of said ring for engaging the adjusting means to prevent rotation of the ring.
4. In a device for securing guide pins in a support the combination with a support having a cylindrical hole therein and a lateral groove in the wall of said hole, a snugly fitting pin arranged to be inserted in said hole, a lateral groove in said pin, a ring in said pin groove conforming in cross sectional contour to the shape of said support groove and arranged to be expanded in 45

50

55

60

65

70

75

said support groove to hold said pin rigidly against longitudinal movement, and movable means in said pin for expanding said ring.

5. A device of the character described comprising a support having an opening therein for a leader pin and an annular groove in the wall of said opening, a snugly fitting pin for insertion in said opening and having a lateral groove for alignment with said support groove, a resilient member in said pin groove and normally below the cylindrical surface of said pin, movable members radially spaced in said pin and engaging the inner surface of said resilient member, and means within said pin and cooperating with said movable members to releasably force said resilient member beyond the surface of said leader pin and into frictional locking engagement with said support groove. 80 85 90

6. A device of the character described comprising a support having an opening therein for a leader pin and an annular groove arcuate in cross section in the wall of said opening, a snugly fitting pin for insertion in said opening and having a lateral groove of substantially the same width as the support groove and arranged for alignment therewith, a resilient member in said pin groove and normally below the cylindrical surface of said pin and having a cross sectional contour conforming substantially to the contour of said support groove, movable members radially disposed in said pin and engaging the inner surface of said resilient member, and means within said pin and cooperating with said movable members to releasably force said resilient member beyond the surface of said leader pin and into frictional locking engagement with said support groove. 95 100 105

7. A leader pin for insertion in a snugly fitting opening in a support, a plurality of radially disposed laterally movable members in said pin, resilient means normally within the contour of said pin and completely enclosing said radial members to prevent the access of dirt thereto, and adjustable means in said pin and cooperating with said radial members to move said resilient means beyond the contour of said pin and into locking engagement with the walls of said opening. 110 115 120
